US0D1064669S

(12) **United States Design Patent** (10) Patent No.: **US D1,064,669 S**
(45) Date of Patent: ** Mar. 4, 2025

(54) **BACK SEAT EXTENDER CAR SEAT COVER**

(71) Applicant: **Shenzhen Ligao E-commerce Co., Ltd.**, Shenzhen (CN)

(72) Inventor: **Lihua Huang**, Shangrao (CN)

(73) Assignee: **Shenzhen Ligao E-commerce Co., Ltd.**, Shenzhen (CN)

(**) Term: **15 Years**

(21) Appl. No.: **29/910,216**

(22) Filed: **Aug. 17, 2023**

(51) LOC (15) Cl. **06-13**

(52) U.S. Cl.

USPC **D6/611**; D30/118

(58) **Field of Classification Search**

USPC D6/596, 608, 610, 611; D12/203, 221,

D12/416; D30/118

CPC A01K 1/0272; B60N 2/60; B60N 2/6009;

B60N 2/6027

(57) **CLAIM**

The ornamental design for a back seat extender car seat cover, as shown and described.

DESCRIPTION

FIG. 1 is a front perspective view of a back seat extender car seat cover, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an exploded view.

The broken lines in the drawings illustrate the portions of the back seat extender car seat cover, which form no part of the claimed design.

1 Claim, 9 Drawing Sheets
